UNITED STATES PATENT OFFICE.

WILLIAM KNOX CLEVELAND, OF ST. PETERSBURG, FLORIDA.

ADJUSTABLE CAR-STANCHION.

No. 835,881.

Specification of Letters Patent.

Patented Nov. 13, 1906.

Application filed August 9, 1906. Serial No. 329,847.

To all whom it may concern:

Be it known that I, WILLIAM KNOX CLEVELAND, a citizen of the United States, and a resident of St. Petersburg, in the county of Hillsboro and State of Florida, have invented a new and Improved Adjustable Car-Stanchion, of which the following is a specification.

My invention relates to stanchions to prevent the load on flat-cars or similar vehicles from slipping or rolling off; and it consists in an improved hinged construction having a sleeve to keep the two parts of the stanchion proper in line and an improved socket for the lower end of the stanchion.

In the accompanying drawings, which illustrate my invention, Figure 1 is a transverse cross-section of the body of a flat-car, showing a pair of my improved stanchions in position. Fig. 2 is a view of a stanchion on a slightly larger scale as seen from one side of the car. Fig. 3 is a view of a modified form of stanchion. Fig. 4 is a detail of the same. Fig. 5 is a cross-section taken on the line B B in Fig. 4 in the direction of the arrow. Fig. 6 is a cross-section on the line A A in Fig. 2, taken in the direction of the arrow.

Similar reference characters refer to like parts throughout the several views.

Stanchions are used on flat-cars to prevent loads from sliding and rolling off, and while the present method of securing sockets to the sides of the outer sill and driving stout pieces of wood into the same is quite efficient it is very expensive, as the wooden stanchions are usually lost at the unloading of the car. My invention provides a stanchion that is permanently secured to the car under ordinary conditions and which may be moved out of the way, so the car may be unloaded without detaching them from the car.

In the drawings, 1 represents the car-floor, and 2 the sills. A bolt 3 passes through the sills and has threaded ends upon which the nuts 4 are screwed, the nuts being provided with handles, so they can be easily turned back to release the sockets 5. These sockets have bearing-plates 6, which contact with the car-sills, and which have notches 8 in their edges to receive the spring-held bolts 7 of the latches 9. These bolts may be of any desired construction and are provided

to hold the sockets in the proper position to hold the stanchions upright.

The stanchion is formed of two pieces of strong wood 10 and 11, each of which has a strap 40 of flat steel fastened around it by means of rivets 12 and screws 13. The two parts are hinged to each other so that the part 10 may swing back, as shown in dotted lines in Fig. 1. The hinge 14 is fitted into slots in the straps, as shown in Fig. 2. To keep the two parts 10 and 11 in line with each other, I provide a sleeve 15, which snugly fits the back of the two parts 10 and 11 where they join when pushed down to the position shown in Fig. 1. This sleeve has inturned lips 15^a, which slide in grooves 16 in the sides of the stanchion just back of the straps. Bolts 17 extend through the slots 18 in the stanchions and through the sides of the sleeves, and thus hold the sleeve in its proper shape.

At the upper ends of the stanchions are caps 19, having eyes 20 secured thereto. Lengths of chain 21 are attached to these caps and provided at their free ends the hooks 22. These chains when connected at the middle of the car will prevent the stanchions being snapped off when too great a load comes against them.

In Figs. 3, 4, and 5 I have shown a modified form of stanchion which is formed of two pieces of pipe 25 and 26, secured together by the hinge 28. The sleeve 34 is held from opening by the bolts 29, which pass through the slot 30 in the stanchion. The cap 31 at the upper end of the stanchion is provided with a chain 21, as before described. The socket 31 on plate 32 are similar to those above described. Instead of a single bolt 3 to hold the stanchions in position I may employ short bolts 33 for each of the sockets.

While I have shown two forms of stanchion, it is evident that any desired cross-section and material may be employed.

Having now explained my improvements, what I claim as my invention, and desire to secure by Letters Patent, is—

1. In a stanchion for railway-cars, the combination of a socket, means to secure the same to the car-body, a stanchion formed of two parts hinged together, a sleeve slidable on said stanchion and adapted to hold the two parts in line with each other, and means to hold the stanchion in upright position.

2. A stanchion for cars, comprising two sections hinged together, a sleeve to hold the sections in line with each other, a socket for the stanchion, and means to hold the socket in position on the car.
3. A stanchion for railway-cars, comprising two sections hinged together, metal straps extending around the said sections, a sleeve fitting the sides and rear of the sections at their adjoining ends, and having inturned lips to fit in grooves in said sections adjacent to the straps, and bolts to prevent the sleeve from spreading, said bolts passing through slots in the sections.
4. A stanchion for railway-cars, comprising two sections hinged together, a sleeve slideable on said sections and adapted to hold

the same in line with each other, a cap at the upper end of the stanchion, a chain connected to said cap, a socket for the lower end of the stanchion, a bolt passing through the socket and stanchion to hold the same in place on the side of the car-body, a nut on the end of the bolt, and a spring-latch adapted to engage in a notch in the socket to hold the stanchion in upright position.

In testimony whereof I have signed my name to this specification in the presence of two subscribing witnesses.

WILLIAM KNOX, CLEVELAND.

In presence of—

B. J. FARMER,
GRANT J. AIKIN.
